CHEST

Ernest Herrmann, Hillsdale, N. J., assignor to Heywood-Wakefield Company, Gardner, Mass., a corporation of Massachusetts

Application March 14, 1955, Serial No. 35,035

Term of patent 7 years

(Cl. D33—6)

Fig. 1 is a front perspective view of a chest embodying my new design;

Fig. 2 is an enlarged fragmentary cross section on the line 2—2 of Fig. 1;

Fig. 3 is an enlarged fragmentary cross section on the line 3—3 of Fig. 1; and

Fig. 4 is an enlarged perspective view illustrating one of the drawer pulls in detail, the concave front thereof being stippled to indicate contrast.

The dominant features of the design reside in the portions shown in full lines.

I claim:

The ornamental design for a chest, substantially as shown and described.
